CLAIM

The ornamental design for a retaining rim for a coffee pot or the like, as shown and described.

DESCRIPTION

FIG. 1 is a perspective view of a retaining rim for a coffee pot or the like showing our new design, the broken lines showing a coffee pot being for illustrative purposes only, and forming no part of the claimed design;

FIG. 2 is a front elevational view thereof;

FIG. 3 is a side elevational view thereof, the opposite side being identical; and

FIG. 4 is a top plan view thereof.

FIG. 5 is a bottom plan view thereof.
